(57) **CLAIM**

The ornamental design for a vehicle mirror support arm, as shown and described.

DESCRIPTION

FIG. 1 is a top perspective view of the vehicle mirror support arm design;

FIG. 2 a bottom perspective view of the vehicle mirror support arm design;

FIG. 3 is a rear perspective view of the vehicle mirror support arm design;

FIG. 4 is a front perspective view of the vehicle mirror support arm design;

FIG. 5 is a rear elevation view of the vehicle mirror support arm design;

FIG. 6 is a front elevation view of the vehicle mirror support arm design;

FIG. 7 is a left side elevation view of the vehicle mirror support arm design;

FIG. 8 is a right side elevation view of the vehicle mirror support arm design;

FIG. 9 is a top plan view of the vehicle mirror support arm design; and,

FIG. 10 is a bottom plan view of the vehicle hood mirror design.

In the drawings, the broken lines showing the carrier arm of the mirror assembly, various bolt holes, and the rear face of the receiver connecting to the support arm form no part of the claimed design.
